 Bigelow-Sanford Carpet Co., Inc., Thompson-
 ville, Conn., a corporation of Massachusetts

Application April 4, 1942, Serial No. 437,662

9 Claims. (Cl. 139—9)

This invention relates to improvements in the weaving of pile fabrics on looms of the sort in which the pile yarn is carried on tube frames which are wiped in through the warp. Its object is to eliminate, as a factor in determining the pile tuft height, differences in the length of yarns protruding from the tubes of one tube frame as compared with the length of yarns protruding from the tubes of other tube frames.

In looms of this character there is a succession of tube frames, each frame having one or more spools carrying pile yarns which are threaded through and protrude below the yarn tubes. For reasons which are well known in the art and therefore require no explanation, although the protruding yarns in each row may be of substantially equal length, the yarns protruding from the tubes of one frame may be longer than the yarns protruding from the tubes of other frames. When the row of longer protruding yarns are turned up by the comb, a row of tufts is produced which is of greater height than the tufts of other rows. This extra height of the tufts must be cut off and in the aggregate the cut-off portions amount to a serious waste and loss.

The object of my invention is to eliminate this waste and loss. According to my invention the lifting of the wiped-in yarns is stopped as soon as their ends are lifted to a predetermined desired level below the upper surface of the breast beam. The depending ends of the yarns of all rows to be turned up are, accordingly, of exactly the same length so that the turned-up tufts of all frames are of the same height and there are no tuft rows higher than others which require cutting off. The turned-up tufts of my invention need not be cut off at all or, if cut off, only a negligible amount need be cut off to bring all the tufts to the same desired height.

In the drawings—

Fig. 1 is a side elevation view of an Axminster loom embodying my invention;

Fig. 2 is a detail plan view of parts near the breast beam;

Fig. 3 is a vertical section on the line 3—3 of Fig. 2;

Fig. 4 is a horizontal section on the line 4—4 of Fig. 1;

Fig. 5 is a side elevation view partly in section on the line 5—5 of Fig. 4;

Fig. 5A is a vertical section on the line 5A—5A of Fig. 5;

Fig. 6 is a section on the line 6—6 of Fig. 1 on enlarged scale;

Fig. 7 is a detail vertical section of a lost motion

connection between the parts of the clutch arm lift rod 16;

Figs. 8, 9, 10, 10A, 11, 12 and 13 are diagrammatic views illustrating the sequence of operations performed by the preferred embodiment of my invention, and

Fig. 14 is a wiring diagram.

The loom shown in the drawings includes a breast beam 2 (Fig. 1) supporting the fabric 4 as it is woven. The backing warps are shown at 5. The weft is inserted by the usual needle and is beaten up by the lay 6 carrying reed 8. The pile yarn is inserted from a tube frame 10, constituting one of a series which may be delivered over the weaving point by the conventional chain mechanism. Successive tube frames are removed from the chain and wiped in by means of the clutch arms 12 (one of which is shown) raised and lowered around pivot shaft 14 by rod 16 pivoted at 18 to one of the arm and at the other end 20 to a lever 22 rotatably mounted at 24 on the frame and carrying a cam follower 26 urged against lift cam 28 by the usual spring, not shown. The cam 28 is shaped differently from the usual lift cam, as will be described, and is mounted on the loom shaft 30 which rotates counter-clockwise, as indicated, once per loom cycle.

The wiped-in pile yarn is turned up by the usual comb 32.

According to my invention, I employ a detecting mechanism which acts to stop the upward movement of the tubes when the lower extremities of the tuft yarns have reached a predetermined level below the upper surface of the breast beam. The holding weft is then inserted and beaten up, the draw-off takes place and the depending tuft yarns are turned up by the comb.

In the preferred embodiment of my invention, hereinafter described, the detecting mechanism comprises a light source and a photo-electric cell, the light beam from the former being prevented from reaching the latter by the interposed depending tuft yarns until they are lifted above the beam, when the beam reaches the cell and sets in motion mechanism which immediately stops the upward movement of the tubes.

As shown in detail in Figs. 1, 2, 3 and 6, a light source 40 and a photo-electric cell 42 are both mounted on a platform 44. The light 40 is enclosed in a glass tube 43 surrounded by the sheathing 41 which has a slot 41a directing the light at the cell 42. The cell 42 is enclosed in a cylindrical glass tube 45 surrounded by concentric, cylindrical sheathings 46 and 47. The outer

sheathing 46 is secured to the platform and the inner sheathing 47 is rotatable within the sheathing 46 and is formed on one end (Fig. 2) with a finger piece 47b by which it may be rotated. The sheathing 46 has a narrow slot 46a in alignment with the light source 40, the cell 42 and the slot 41a in the sheathing 41 surrounding the light. The rotatable sheathing 47 is also slotted at 47a so that rotation of sheathing 47 adjusts the size of opening between the light source and the cell to insure that a very thin beam of light issuing from the source is concentrated on the cell and that the cell is shielded from extraneous light.

The platform 44 carrying the light source and cell can be raised and lowered between the upper position shown in Figs. 1 and 9 and the lower position shown in Fig. 8. When in the upper position, and the clutch arms 12 are in their lowest wipe-in position (Fig. 9), light 40 and cell 42 are disposed on opposite sides of a small portion of the line of depending yarns, indicated at 49 in Fig. 2, and the cell and light are spaced from each other sufficiently to receive the yarns between them. To assist proper reception of the yarns between the light and cell, I provide a suction nozzle 80 (Fig. 3) projecting through aperture 82 in platform 44 and communicating by the fitting 84 and flexible tube 86 with a vacuum pump 88. Thereby, when the pump 88 is operating, air is drawn down the nozzle 80 to draw the depending yarns ends downwardly between the sheathing 41 surrounding the light and the sheathing 46 surrounding the cell.

The sequence of operations of my loom, the details of whose construction will later be described, are shown by Figs. 8 to 13 inclusive in which, for clarity, the tuft yarn being wiped in is shown of exaggerated size in comparison with the woven fabric. The weaving cycle and the operation of the loom may in all respects be of conventional character up to the wiping in of the pile tuft yarns by the tube frames. Also, as is usual, the wipe-in commences by removing a tube frame from the carrier chains by means of the clutch arms 12 and lowering its tubes through the warp. As shown in dotted lines in Fig. 8, the tube frame 10 is tipped slightly to insure proper passage of the pile yarn 49 through the warp and the lowering movement continues until the tubes arrive at their lowermost position relative to the breast beam 2, as shown in full lines in Fig. 8. During the wipe-in operation the platform 44 carrying light 40 and cell 42 begins to rise and is elevated to the position, Fig. 9, in which the depending yarn ends are brought between the light and the cell. The suction of air from tube 86 and nozzle 80 aids in drawing the yarns downwardly between the light and cell.

The upward movement of platform 44 with its light 40 and cell 42 is stopped when the light and cell are brought to the position shown in Fig. 9 and diagrammatically in Fig. 10A. The light is constantly on and with the platform in this position the depending yarns obstruct sufficient of the light so as not to energize the cell 42. As soon as the light has thus been obstructed the circuit to the filament of the cell is completed as will be described.

The tube frame rises until the lower extremities of the depending yarns rise above the line of the slots 41a, 46a and 47a, thereby permitting the light from source 40 to strike cell 42 and energize it. Energizing of cell 42 effects clos-

ing of a circuit effective to apply a brake which abruptly stops the upward movement of tube frame 10.

Thus the lower extremities of the depending yarns 49 are brought to, and stopped at, a level which is a predetermined distance *c* below the upper surface of the breast beam, as shown in Fig. 10A.

The light source 40 and cell 42 are then lowered, as shown in Fig. 11. The holding weft shot 300 is inserted and beaten up by the reed 8, as shown in Fig. 12. The draw-off, shown in Fig. 12, then occurs.

The depending yarn ends are turned up by comb 32, as shown in Fig. 13. The yarn tufts 320 thereby formed are of a predetermined height which is the same for the tufts of all tube frames.

Thereafter the cutters 310 operate, as indicated in Fig. 13, to cut off the yarn depending from the tuft tubes. The cutters need not cut off yarn from the ends of the turned-up tufts because they are all of substantially the same height. If it is desired, however, to cut off the ends of the turned-up tufts, only a negligible amount need be cut off. The loss in tuft yarn, through such trimming, is thus reduced to nothing or to a negligible amount.

The specific construction of the preferred embodiment of loom by which I attain this mode of operation is illustrated in Figs. 1 to 7 inclusive and Fig. 14.

The platform 44 is mounted on the upper extremity of a plate 48 secured by blocks 48a to a slide 50 which is dovetailed for a sliding fit in a groove 52 formed in a fixed bearing member 54 secured to the frame. Raising and lowering of slide 50 is effected by a rack 58 secured to the rear of the slide 50 and meshing with a pinion sector 60 formed on the end of a lever 62 pivoted at 64 to the frame. Lever 62 carries a cam follower 66 adapted to be engaged by the rise 70b of cam 70 (fixed to shaft 30) and to be received within the recess 70a thereof. Slide 50 is urged to its upper position adjacent the breast beam by tension spring 72 fixed at its upper end to pin 73 projecting from the stationary bearing member 54 and at its lower end to a pin 76 fixed to the slide 50. The limit of upward movement of slide 50 is regulated by a stop screw 74 threaded through an aperture in a flange 50a at the bottom of slide 50 and adapted to abut the lower surface 54a of the bearing member 54. A lock nut 78 secures the screw in its adjusted position. As the result of this construction, cam follower 66 will not seat in the bottom of recess 70a of cam 70 when platform 44 is in its upper position of Fig. 1 but will be held away by stop screw 74. The rise 70b of cam 70 is concentric with the axis of shaft 30 and occupies the entire periphery of the cam except for the recess 70a. When the follower 66 is raised by the rise 70b the platform and associated light and cell will move to their lower positions, shown in Fig. 8.

Pivoted at 100 to the rear extremity of the clutch arm 12 shown in Fig. 1 is a rod 102 connected at its lower end to a brake plate 106 (Figs. 1, 4 and 5) slidably mounted in the recess of the U-shaped frame member 108 pivoted at 104 to the frame. Also disposed within this recess, and in front of the plate 106, is a brake shoe 110 of hardened steel retained in place by the cross members 112 and 114 secured across the sides of the U (Fig. 5A) and abutting the flanges 116 and 118 respectively formed on the

opposite ends of the shoe 110 to retain the shoe in place.

When the clutch arms 12 are raised and lowered about pivot 14 by tube frame lift cam 28, plate 106 rises and falls within the U member 108. In accordance with the preferred embodiment of my invention, the movement of the tube frame at the completion of the wipe-in is arrested by stopping the movement of plate 106. For that purpose I provide a brake cam 120 having a surface 120a eccentric to the center of shaft 122 on which the cam is mounted. Shaft 122 is supported by lugs 121 and 123 projecting from the U member 108. Movement of cam 120 from its Fig. 5 position counter-clockwise to its Fig. 1 position presses shoe 110 against brake plate 106 to stop movement of the plate. Such counter-clockwise rotation of cam 120 is effected by rod 124 secured to the cam and urged upwardly by spring 126 (Fig. 1) connected at one end to the lever 124 and at its other end to a portion 128 of the frame.

To effect release of brake cam 120 by clockwise rotation, lever 124 is connected by rod 130 to a lever 132 pivoted at 24 to the frame and carrying a cam follower 134 bearing against cam 136 mounted on shaft 30 and having a rise 136a. When rise 136a rotates lever 132 counter-clockwise lever 124 is rotated clockwise against the action of spring 126 to release the brake. To hold the brake in released position, lever 124 carries rigidly secured to it a latch element 140 adapted to engage a complementary latch member 142 rigidly fixed to an arm 148 pivoted at 144 to a bracket 146 projecting from the frame. The arm 148 is pivotally connected at 158 to a rod 160 attached to the core 162 of a solenoid 164 mounted on U member 108. Rotation of lever 148 to dispose latch 142 in its latching position of Fig. 5 is effected by a tension spring 166 (Figs. 5 and 5A) connected at one end to the flange 168 of a bracket 170 depending from the lever 148 and at its other end to a lug 172 formed on the bracket 146. Such clockwise rotation of lever 148 is limited by a stop screw 176 threaded through lug 172 and abutting the upper edge of lever 148 when the parts are disposed as indicated in Figs. 5 and 5A.

By this construction, the brake cam 120 is released by downward movement of rod 130 and through the action of rise 136a of cam 136 and is locked in released position by the engagement of latch members 140 and 142. When solenoid 164 is thereafter energized, attracting its core 162, lever 148 rotates counter-clockwise to release the latch for immediate application of brake 120 through the action of spring 126.

As stated, application of brake cam 120 arrests sliding movement of brake plate 106 to stop clutch arms 12 in predetermined position at the completion of the wipe-in. The movement of clutch arm 12, at the moment the brake is applied to stop the wipe-in motion, is in an upward direction immediately following the lowering of tube frame 10 through the warp. Such upward movement results from a downward movement of rod 16, effected by cam 28. Since cam 28 may induce a further downward movement of the lower part 16a of rod 16 while its upper part 16b is held against movement, I provide a lost motion between these parts, as shown in detail in Fig. 7. Part 16a telescopes within part 16b. Encircling the part 16b is a compression spring 180 interposed between a collar 182 formed on the lower end of part 16b and a sec-

ond collar 184 which slides freely on the outside of part 16b. The inner part 16a carries a pin 186 extending outwardly of part 16b through opposite elongated slots (one of which is shown at 188 in Fig. 7) formed in the side wall of part 16b. Sliding collar 184 abuts pin 186. Thereby, part 16a will move downwardly within part 16b, compressing spring 180, in the event that part 16b is held stationary during such movement.

In Fig. 14, I have shown the electric circuits employed in the preferred embodiment of my invention. At 200 and 202 are indicated leads from a power source not shown. The lead 200 is connected to one terminal 204 and the lead 202 to another terminal 206 of an amplifier and relay designated generally at 208 of a type common in photo-electric cell circuits. To a third terminal 210 of the amplifier and relay is connected a wire 212 leading to the plate 214 of the photo-electric cell 42. The filament 215 of the cell is connected by wire 216 to one terminal 218 of a switch 220 whose other terminal 222 is connected by wire 224 to a terminal 226 of amplifier and relay 208. The switch 220 has an armature 230 closed by means of the cam follower 232 when the rise 234a of cam 234 engages the follower. As shown in Fig. 1 the cam 234 is mounted on shaft 30 to rotate therewith.

Attached to the further terminals 240 and 242 of amplifier and relay 208 are wires 244 and 246 which are connected respectively to the opposite ends of the aforesaid solenoid 164.

Also connected to the power mains 200 and 202 are wires 250 and 252 respectively. The wire 250 leads to one element 254 and the wire 252 leads to the other element 256 of the aforesaid light 40.

The purpose of the electric circuits diagrammatically illustrated in Fig. 14 is to energize solenoid 164 when light from the source 40 falls on the photo-electric cell 42 and the cell has been rendered operative by the closing of switch 220 through the action of cam 234. Many well-known types of light sources and photo-electric cells are available to function in this manner and, as the particular type chosen forms no part of my present invention, further description of the construction of these parts is believed unnecessary. In practice I have found the device to be more sensitive when a fluorescent type of light source is used.

Switch 220 remains open during the entire loom cycle until platform 44 is in its Fig. 9 position and the light beam is blocked from the cell by the yarn. The switch then closes. As described, the cell is then energized by the light beam striking it when the yarn is lifted above the beam, and brake actuating solenoid 164 is immediately energized and the brake applied. As platform 44 is thereafter lowered (Fig. 11) switch 220 again opens de-energizing solenoid 164 to allow latch member 142 to retract from its Fig. 1 position. But the brake remains on until released by cam 136 pulling downwardly on rod 130. Such release occurs immediately prior to the draw-off movement of Fig. 12.

The tube frame lift cam 28 is preferably not of the usual construction. It descends, as shown at 28a, to the usual low 28b where the tube frame is at its lowest position (Fig. 9). Thereafter it rises at 28c for lifting the tube frame from its Fig. 9 position as shown in Fig. 10. After this rise there is a dwell 28d to hold the tube frame for the beat-up (Fig. 11) followed by a further rise 28e for the draw-off (Fig. 12). In my cam 70 the rise 28c immediately following the wipe-in is

preferably both higher and more gradual than the corresponding rise in the usual lift cam. It is higher to insure that the tube frame is still lifting when the photo-electric cell 42 becomes effective, regardless of the length of yarn protruding from the tube frame. It is more gradual so that the action of the cell is effective to stop the lifting before the yarn ends have passed appreciably above the distance c .

The height of pile tufts, although constant as above stated, is at the same time adjustable in my loom by regulating the setting of the stop screw 14, determining the distance between the upper position of the platform 44 and the upper surface of the breast beam. To accommodate such adjustment, the aforesaid rise 28c on the lift cam must be sufficiently high to insure that the tube frame is moving upwardly when the light strikes the cell for all heights of pile tuft contemplated.

Although the use of a light source and photo-electric cell or similar detecting mechanism is desirable, as the yarn is not contacted thereby, detecting means which lightly contact the yarn may be used. The mechanism for stopping the lifting movement may, of course, be varied considerably and my invention is not to be limited to any of the details described herein except as required by the appended claims.

I claim:

1. In an Axminster loom having a breast beam and wipe-in mechanism including means to lift a tube frame after its row of yarn ends has been wiped in, the combination of detecting means for detecting when the lower extremities of a row of lifting yarn ends have reached a predetermined level below the upper surface of the breast beam, brake means operative to stop the lifting of said tube frame and means connected to said brake means and responsive to said detecting means to actuate the brake means and to stop the lifting of said tube frame when the extremities of said yarn ends have reached said level.

2. In an Axminster loom having a breast beam and wipe-in mechanism including means to lift a tube frame after its row of yarn ends has been wiped in, the combination of detecting means for detecting when the lower extremities of a row of lifting yarn ends have reached a predetermined level below the upper surface of the breast beam, brake means to stop the lifting of said tube frame, electrically operated mechanism for effecting the application of said brake means, an electric circuit connected to said electrically operated means to operate the same, said circuit being closed by said detecting means to apply said brake means and to stop the lifting of said tube frame when the extremities of said yarn ends have reached said level.

3. In an Axminster loom having a breast beam and wipe-in mechanism including means to lift a tube frame after its row of yarn ends has been wiped in, the combination of brake means operative to stop the lifting of said tube frame, electrically operated mechanism for effecting the application of said brake means, an electric circuit connected to said electrically operating means to operate the same, a photo-electric cell which, when energized, completes said circuit, a light source for energizing said cell, the light source and cell being so located that the beam of light which energizes said cell is at a predetermined level below the upper surface of the breast beam and said beam is obstructed by the yarn ends while they are approaching said predetermined level during said lifting movement and becomes

unobstructed to energize the cell and to stop said lifting movement when the extremities of said yarn ends have reached said level.

4. In an Axminster loom having a breast beam and wipe-in mechanism including means to lift a tube frame after its row of yarn ends has been wiped in, a brake for stopping said lifting movement, means for applying said brake, a pair of elements, aligned with each other along a predetermined path, operating, when said path is unobstructed by yarn ends, to actuate said brake-applying means, a platform on which said elements are mounted and means for moving the platform to dispose said path in position to be obstructed by the yarn ends during said lifting movement and at such predetermined level below the breast beam that the yarn ends are lifted out of said path and said lifting movement is stopped when the extremities of the yarn ends have reached said level.

5. In an Axminster loom having a breast beam and wipe-in mechanism including means to lift a tube frame after its row of yarn ends has been wiped in, a brake for stopping said lifting movement, means for applying said brake, a pair of elements, aligned with each other along a predetermined path, operating, when said path is unobstructed by yarn ends, to actuate said brake-applying means, a platform on which said elements are mounted, means for moving the platform to dispose said path in position to be obstructed by the yarn ends during said lifting movement and at such predetermined level below the breast beam that the yarn ends are lifted out of said path and said lifting movement is stopped when the extremities of the yarn ends have reached said level, and an adjustment for regulating the distance of said path below the breast beam to vary the distance of the extremities of the yarn ends below the breast beam when they are so stopped.

6. In an Axminster loom having a breast beam and wipe-in mechanism including means to lift a tube frame after its row of yarn ends has been wiped in, a brake for stopping said lifting movement, means for applying said brake, a pair of elements, aligned with each other along a predetermined path, operating, when said path is unobstructed by yarn ends, to actuate said brake-applying means, a platform on which said elements are mounted, means for moving the platform to dispose said path in position to be obstructed by the yarn ends during said lifting movement and at such predetermined level below the breast beam that the yarn ends are lifted out of said path and said lifting movement is stopped when the extremities of the yarn ends have reached said level, and suction means for drawing the yarn ends downwardly between said elements as the platform is moved to dispose said path at said level.

7. In an Axminster loom having a breast beam, the combination of detecting means for detecting when the lower extremities of a row of lifting yarn ends have reached a predetermined level below the upper surface of the breast beam, said means comprising a lamp and a photo-electric cell so related that the beam of light from the lamp may strike said cell and thereby energize it, a support carrying said lamp and cell, means to raise said support to such position that said beam of light is at a predetermined level below the upper surface of the breast beam and said lamp and said cell are on opposite sides of the yarn ends depending from a

row of tube frames after they have been wiped in, wipe-in mechanism including means to wipe in said yarn ends and to raise the tube frame to a position in which the extremities of said yarn ends are removed from the path of said beam of light whereby said beam of light may energize said cell, an electric circuit through which a current of electricity flows when said cell is energized, brake means operative to stop said lifting movement and electrically operating brake-applying means in said circuit actuated when said cell is energized to stop the lifting of said tube frame with the extremities of the yarn ends at said predetermined level, and a comb to turn up said yarn ends after their lifting movement has stopped.

8. In an Axminster loom adapted to stop the lifting of the tube frame when the lower extremities of its yarn ends reach a predetermined level below the breast beam after the wipe-in, the combination of a breast beam, wipe-in mechanism including a cam adapted to lift the extremities of the yarn ends higher than said level, detecting means for detecting when the lower extremities of the yarn ends have reached said level, brake means for stopping said

lifting movement and means responsive to said detecting means and connected to said brake means to stop the lifting of said tube frame when the extremities of its yarn ends have reached said level.

9. In an Axminster loom adapted to stop the lifting of the tube frame when the lower extremities of its yarn ends reach a predetermined level below the breast beam after the 10 wipe-in, the combination of a breast beam, wipe-in mechanism including a cam adapted to lift the extremities of the yarn ends higher than said level, detecting means for detecting when the lower extremities of the yarn ends have reached said level, brake means for stopping said lifting movement, means responsive to said detecting means and connected to said brake means to stop the lifting of the tube frame when the extremities of its yarn 15 ends have reached said level, and a lost motion connection between said cam and the tube frame to compensate for the effort of the cam to lift the extremities of the yarn ends higher than said level.
